UNITED STATES PATENT OFFICE.

ELIHU THOMSON, OF SWAMPSMOTT, MASSACHUSETTS, ASSIGNOR TO GENERAL ELECTRIC COMPANY, A CORPORATION OF NEW YORK.

SYSTEM OF DISTRIBUTION.

1,105,716.

Specification of Letters Patent.

Patented Aug. 4, 1914.

Application filed August 4, 1911 Serial No. 642,371.

To all whom it may concern:

Be it known that I, ELIHU THOMSON, a citizen of the United States, residing at Swampscott, county of Essex, State of Massachusetts, have invented certain new and useful Improvements in Systems of Distribution, of which the following is a specification.

My invention relates to systems of distribution, particularly for lighting, and has special reference to those cases in which a flat rate is charged for power with a restriction as to the maximum amount of current to be consumed.

My invention has for its object the provision of a novel current limiting device for preventing the satisfactory operation of an electric installation when the maximum amount of current allowed by the consumer's contract is exceeded.

The device of my invention is applicable to alternating current circuits only and is particularly advantageous on local circuits, each having its own transformer through which energy is supplied from the main circuit.

I accomplish the desired result of producing a reduction in voltage in the local circuit when the current therein exceeds a predetermined amount, by providing a pair of coils, through which passes the energy from the main circuit to the local circuit, and which are normally in close, mutually inductive, relation, but which when traversed by current exert a repulsive force on each other and are relatively movable so as to separate when the current in them exceeds a predetermined amount. When the coils are in their normal position they introduce but little reactance into the circuit but when they move apart each coil has considerable leakage flux which increases its reactance and reduces the voltage in the local circuit. These two coils may advantageously be made the primary and secondary of a transformer, particularly if the system is one in which each local circuit has its own transformer through which it receives its energy from the main circuit.

My invention will best be understood by reference to the accompanying drawing which shows diagrammatically a system of

distribution arranged in accordance with my invention.

In the drawing, A represents the main supply circuit of approximately constant potential and B the local circuit, such as a lamp circuit in a house, containing the lamps or other translating devices b designed for operation on constant potential.

C represents a transformer core carrying the primary winding D connected to the supply circuit and the secondary winding E connected to the local circuit. The secondary winding is movable axially within the primary winding. Its normal position is at the extreme bottom of its travel, slightly below the position in which it is shown in the drawing. When it is in its normal position the two windings D and E are in close, mutually inductive, relation, like the coils of any transformer with good regulation, but when the coil E moves to a higher position both coils have considerable leakage flux,

which, as is well understood in the art, produces the same result as reactance in series with the windings; that is, it lowers the voltage of the local circuit B. The coil E is carried by suitable pivoted members F, one on each side of the core, and the weight of the coil is partly compensated for by a tension spring G acting on the other end of each of the members F. The primary coil D has an L-shaped cross section. The object of shaping the coil thus is to bring a portion of the primary turns below the secondary coil so as to produce a repulsive force between the coils acting in an axial direction when the coils are traversed by current while at the same time permitting the coils to lie in close, mutually inductive, relation in normal operation. The core C has three legs with the coils surrounding its middle leg. The outer legs extend inward above the primary coil F so as to increase the leakage flux of the coil E when it is in its raised position.

The operation of the system will be obvious from the foregoing description. Normally the coil E remains in its lowest position in close, mutually inductive, relation to the primary coil D, so that normal voltage is maintained on the lamps b. When too many lamps are turned on so that the cur-

rent exceeds a predetermined amount, the repulsive force between the two transformer coils acts to raise the secondary coil E and produce a leakage reactance in the transformer which dims the lamps. To restore the lamps to normal brilliancy it is necessary for the consumer to turn off enough to reduce the current to an amount within the proper limit.

10 I do not desire to limit myself to the particular arrangement and connections shown and described, but contemplate changes within the scope of the appended claims.

What I claim as new and desire to secure 15 by Letters Patent of the United States, is:—

1. In combination with a main supply circuit of approximately constant potential, a local circuit containing current translating devices designed for operation on constant 20 potential, and a transformer, through which said local circuit is supplied from the main circuit, comprising two windings relatively stationary in normal operation but automatically relatively movable when the load 25 on the transformer exceeds a predetermined amount.

2. In combination with a main supply circuit of approximately constant potential, a local circuit containing current translating devices designed for operation on constant 30 potential, and a transformer, through which said local circuit is supplied from the main circuit, having its windings normally in close, mutually inductive, relation, 35 but relatively movable under the repulsive effect of currents therein exceeding a prede-

termined amount, and having supporting means for said windings permitting said relative movement when the currents in said windings exceed predetermined amounts. 40

3. In combination with a main supply circuit of approximately constant potential, a local circuit supplied therefrom containing devices designed for operation on constant potential, a pair of coils through which 45 passes the energy supplied from the main to the local circuit, said coils being normally in close mutual inductive relation but producing a repulsive force on each other when traversed by current, and supporting means 50 for said coils permitting relative movement of said coils when said repulsive force exceeds a predetermined amount.

4. The combination with a main supply circuit of approximately constant potential, 55 a local circuit containing current translating devices designed for operation on constant potential, a winding in each of said circuits and in close, mutually inductive relation to each other in normal operation, one of said 60 windings having a portion of its turns axially displaced with respect to the other winding, said windings being relatively movable axially when the repulsion effect between said windings exceeds a predetermined amount.

In witness whereof, I have hereunto set my hand, this first day of August, 1911.

ELIHU THOMSON.
